UNITED STATES PATENT OFFICE.

DANIEL J. KELLY, OF CHICAGO, ILLINOIS.

TOY.

1,260,205.

Specification of Letters Patent. Patented Mar. 19, 1918.

Application filed November 12, 1917. Serial No. 201,588.

To all whom it may concern:

Be it known that I, DANIEL J. KELLY, a citizen of the United States, residing at Chicago, in the county of Cook and State of Illinois, have invented certain new and useful Improvements in Toys, of which the following is a specification, reference being had to the accompanying drawings.

This invention relates to toys, and more particularly to a mechanical toy of that general character having relatively movable figures or manikins.

It is the primary purpose and object of this invention to provide a manually operable toy of very simple and durable construction, in which the figures or manikins are mounted upon a single operating element, in the actuation of which a realistic simulation of the physical movements of the characters represented will be produced.

It is another object of my invention to provide a toy of the above character which will be interesting and amusing to juveniles and can be manufactured and sold at relatively small cost.

With the above and other objects in view, my invention consists in the novel features of construction, combination, and arrangement of parts to be hereinafter more fully described, claimed and illustrated in the accompanying drawing, in which:—

Figure 1 is a perspective view illustrating one embodiment of my improved toy;

Fig. 2 is a longitudinal section;

Fig. 3 is a section taken on the line 3—3 of Fig. 2;

Fig. 4 is a perspective view showing a slightly modified form of the device; and

Fig. 5 is a perspective view illustrating still another modification.

Referring in detail to the drawing, and more particularly to Figs. 1, 2 and 3 thereof, 5 designates an elongated rectangular frame, which is formed from a single length 45 of sheet metal of requisite width and length. In the parallel side portion 6 of this frame, the ends of a shaft 7 are rotatively engaged, said shaft being provided intermediate of its ends with a crank 8, having a suitable 50 handle 9 formed on one end exteriorly of the frame 5. A narrow strip of resilient metal 10 is longitudinally bowed and has its end portions slidably engaged through 55 openings 11 in the opposite ends of the frame 5. The extremities of this resilient metal strip are turned upon themselves as

shown at 12, to provide stops whereby the displacement of the ends of the strip from the openings 11 is prevented. The resilient metal strip 10 is centrally bent to provide 60 an offset sleeve 14 on the underside of said strip, which is loosely engaged upon the medial portion of the crank 8.

In the embodiment of the invention as shown in Fig. 1, manikins 13, illustrative 65 of boxers, are secured upon the bowed strip of metal 10. These manikins face each other and have their arms raised or extended in simulation of the pose assumed by boxers. They are positioned upon the metal 70 strip 10 on opposite sides of the crank 8 in the shaft 7.

In the operation of this form of the invention, the crank shaft 7 is oscillated or rapidly rotated in the frame in reverse directions. In each downward movement of the crank 8, the metal strip 10 is straightened out, the ends of said strip bearing upon the ends of the frame 5. The manikins mounted upon this strip are thereby caused 80 to approach each other, so that they will appear to be delivering blows upon the opponent's body. After manipulating the crank shaft in this manner several times, it is suddenly given a complete rotation. In 85 the upward movement of the crank 8, the metal strip 10 is bowed to a greater extent so that the figures on said strip are moved away from each other. As the crank suddenly moves downwardly and the strip 10 90 is straightened, the figures will move toward each other with great rapidity, giving a realistic simulation of the rushing tactics of boxers.

My improved toy, operated in the manner 95 explained, provides a very interesting and amusing device which will be attractive to children. It is manifest, of course, that various birds, animals, or other figures may be mounted upon the resilient metal strip 100 10, instead of the boxers above referred to. I have also found that by resorting to slight modifications in the relative arrangement of the strip 10 and the crank shaft, other operations or movements of the figures on the 105 strip may be produced. Several of these modifications I have illustrated in the accompanying drawing, which I will now more particularly describe.

In Fig. 4, the metal strip 10' has the 110 sleeve 14' formed therein projecting upwardly so that the crank 8 in the shaft 7 is

positioned above said strip, instead of below the same as in the form of the invention above described. From the sleeve 14', the metal strip 10' is slightly bowed upwardly 5 toward its opposite ends. The ends of this resilient metal strip are slidably engaged in the ends of the frame in the same manner as above referred to. On the two bowed sections of the metal strip 10', figures 13', 10 representing animals, such, for instance, as bulls, are mounted.

In the operation of this form of the device, owing to the fact that the metal strip 10' is bowed upwardly on each side of its 15 center, in the downward movement of the crank 8, there will be a more sudden inward movement of the heads of the animals toward each other, the central portion of the metal strip being forced downwardly below 20 the plane of its end portions which are engaged through the slots in the ends of the frame 5. Thus the animals will appear to be butting or fighting each other.

In Fig. 5 of the drawing, I have illustrated another form of my invention where- 25 in a plurality of longitudinally bowed metal strips 10^a are provided, said strips extending through spaced openings provided in one end of the frame 5. The terminal portion 30 of each strip extending exteriorly of the frame is turned or coiled on itself, as at 12' to limit its inward movement, and the other terminal of each metal strip is bent upon itself to form a cuff or sleeve 14^a which is 35 engaged upon one of the series of cranks 8' formed in the shaft 7'. This shaft is mounted in the longitudinal side portions of the frame 5, adjacent the opposite end of the frame from that through which the resilient 40 metal strips extend. In this embodiment of my invention, figures, representing runners shown at 13^a, are mounted upon the several strips 10^a. The cranks 8' are disposed in different radial lines with respect to each 45 other and the figures 13^a are secured upon the respective metal strips at different distances from the ends thereof. Thus when the crank shaft is operated, and the resilient metal strips are alternately bowed and 50 straightened as they are moved longitudinally with respect to the frame, the figures or manikins on said strips will appear to be running. Many other novel and amusing 55 toys might also be produced utilizing the same operating principle.

From the foregoing description, taken in connection with the accompanying drawing, the construction and manner of operation of the several described embodiments of the 60 invention will be readily understood. The toy may be readily operated by even very young children and as no springs or other easily breakable elements are employed in its construction, it will be apparent that the 65 device is exceedingly durable. The toy can

be manufactured in various sizes and the number of resilient metal strips on which the figures or manikins are mounted may be multiplied, as desired.

While I have herein shown and described 70 the preferred construction and relative arrangement of the various parts, it is, of course, to be understood that the device is susceptible of considerable modification therein and I, therefore, reserve the privilege of adopting all such legitimate changes 75 as may be fairly embodied within the spirit and scope of the invention as claimed.

Having described my invention, what I 80 claim is:—

1. A toy comprising a frame, a bowed resilient metal strip longitudinally movable in the frame, a figure mounted on said strip, and means mounted in the frame and operatively connected to said metal strip to 85 reciprocate the same in the frame.

2. A toy comprising a frame, a bowed resilient metal strip longitudinally movable in the frame, a figure mounted on said strip, and an operating shaft mounted in the 90 frame having a crank operatively connected to said metal strip to reciprocate the strip in said frame.

3. A toy comprising a metal frame, a bowed resilient metal strip, said frame having 95 a slot in one end through which one end of the strip is movably engaged, a figure mounted on said metal strip, and a shaft mounted in the frame and having a crank operatively connected to said metal strip to 100 reciprocate the strip with respect to the frame.

4. A toy comprising a metal frame, a bowed resilient metal strip, said frame having a slot in one end through which one 105 end of the strip is movably engaged, a figure mounted on said metal strip, the terminal of said metal strip being coiled upon itself to provide a stop to limit the movement of said strip in one direction, and a shaft mounted 110 in the frame and having a crank operatively connected to said metal strip to reciprocate the strip with respect to the frame.

5. A toy comprising a metal frame, a longitudinally bowed resilient metal strip, the 115 opposite ends of the frame being provided with slots through which the end portions of the strip are engaged, confronting toy figures mounted on said bowed metal strip, and a shaft mounted in the frame and having a crank centrally connected to the metal strip to reciprocate said strip with respect to the frame and simultaneously flex said strip.

6. A toy comprising a rectangular sheet metal frame having slots in its opposite ends, a longitudinally bowed resilient metal strip 125 slidably engaged at its ends through said slots, confronting toy figures mounted upon said bowed metal strip, and a shaft rotatably mounted in the frame and provided with a 130

crank, said metal strip being centrally bent upon itself to provide a sleeve loosely engaged on said crank, whereby in the rotation of the crank, said metal strip is reciprocated with respect to the frame and simultaneously flexed.

In testimony whereof I hereunto affix my signature in the presence of two witnesses.

DANIEL J. KELLY.
